CLAIM

The ornamental design for a corner element for a roof rack,
as shown and described.

DESCRIPTION

FIG. 1 is a top, left side perspective view of a corner element
for a roof rack;

FIG. 2 is a front plan view thereof;

FIG. 3 is a top plan view thereof;

FIG. 4 is a bottom plan view thereof;

FIG. 5 is a left side plan view thereof;

FIG. 6 is a right side plan view thereof; and,

FIG. 7 is an isometric view of FIG. 1 thereof.
